UNITED STATES PATENT OFFICE.

CHARLES R. PIERCE, OF WASHINGTON, DISTRICT OF COLUMBIA.

ADVERTISING APPARATUS.

1,115,103.

Specification of Letters Patent. Patented Oct. 27, 1914.

Application filed March 28, 1913. Serial No. 757,389.

To all whom it may concern:

Be it known that I, CHARLES R. PIERCE, a citizen of the United States, residing at Washington, in the District of Columbia, 5 have invented certain new and useful Improvements in Advertising Apparatus, of which the following is a specification.

This invention relates to improvements in advertising apparatus and has for its object 10 to provide mechanism whereby a novel illuminating effect may be produced designed to attract attention wherever the same may be on exhibition.

The leading feature of my invention is 15 to produce a variety of color effects particularly arranged to be displayed at night, and to this end I have devised a simple, efficient, and inexpensive apparatus serving as an advertising medium.

With the above and other objects in view 20 my invention consists in the combination arrangement, and details of construction disclosed in the drawings and specification, and then more particularly pointed out in the appended claims.

In the drawings, wherein similar reference characters designate similar parts throughout the respective views, Figure 1 is 25 a sectional elevation of my invention, Fig. 2 is a front detail elevation of a mirror to be described, Fig. 3 is a cross sectional view of 30 my invention, Fig. 4 is an end sectional elevation of a revolving transparent member, Fig. 5 is an elevation, partly in section, of a 35 modification of my invention, Fig. 6 is a detail view of a transparently speckled mirror, Fig. 7 is a side elevation of said modification, and Fig. 8 is a detail view of a cut 40 glass revolving member.

Referring to the drawings which are 45 merely illustrative of my invention, a suitable standard 1 is shown, which, as illustrated, consists of four arms radiating from a central support 2. At diametrically opposite 50 points of said standard extend upwardly the shaft bearings 3 and 4 in which are revolvably mounted the shafts 5 and 6, and mounted upon the said shafts are the relatively large bevel wheels 7 and 8 in which are counter- 55 sunk in confronting relation mirrors 9 and 10. Mounted also upon the free ends of said shafts are two segmental translucent members 11 and 12 each of which may be com-

posed of a plurality of differently-colored glasses in order to enhance the brilliant 55 effect produced. It will be noticed that while member 11 is vertically disposed member 12 is horizontally disposed, or that one is in a plane at right angles to the other. Said members 11 and 12 snugly surround a 60 relatively longer segmental member or ring 13 also composed preferably of a plurality of colored glasses, said member 13 being in contour almost a complete circle, and being mounted on the upper end of a sleeve 14 65 which is arranged to revolve in a plane at right angles with respect to that of members 11 and 12.

Sleeve 14 is preferably hollow and is arranged to bear upon a washer 15 resting on 70 the base of the standard, and to surround the smooth surface of a relatively narrow and tubular member 16 which is for a portion of its length screw-threaded into the standard 2. The sleeve 14 terminates short of the 75 upper end of the tubular member 16, and a washer 17 rests thereupon surmounted by the threaded tubular portion 18 of an electric lamp 19 or by any other source of light, said threaded portion engaging the tubular member 16. The sleeve 14 is removable from member 16 and will be loosely mounted thereon so as to revolve freely. The tubular member 16 communicates with a channel 17' 80 formed upon the standard 1 so that through 85 an outlet (not shown) opening into said channel the insulated electric wires 20 may pass, extending upwardly therein to the lamp 19. A suitable globe 21 will preferably surround said lamp 19. Mounted upon 90 sleeve 14 is a worm wheel 22 designed to be set in motion by the worm 23 operated from any suitable source of power. The bevel wheel 24 meshing with bevel wheels 7 and 8 is also fixed on sleeve 14. 95

From the above description the operation of my invention will be clear. When the worm wheel is rotated sleeve 14 will revolve and so will the bevel wheel 24, thereby causing member or ring 13 to revolve in a horizontal plane and members 11 and 12 to revolve vertically. It will be understood that the lamp 19 will be under illumination when sleeve 14 is revolved so that the light may play upon members 11, 12 and 13. As the 100 105 member or ring 13 revolves in a plane at

right angles to members 11 and 12 it will be seen that a variety of colors and colored effects will be produced as the rays of light pass through said members, and these brilliant rays will fall upon the mirrors 9 and 10 and will be reflected, thereby enhancing the richness of the color effects.

The modification shown relates only to the manner in which the rays of light may be reflected to the best advantage. It will be understood that the relatively large globe 10 will be mounted in position upon suitable holding members 26. In Fig. 1 portions of the shaft bearings 4 and 4 extend alongside 15 of the bevel wheels 7 and 8 carrying the mirrors 9 and 10. The principle underlying my invention does not contemplate the use of the shaft bearings 3 and 4 in all situations. For example either member 7 or 8 may be 20 mounted on the shaft 27 secured concentric with a cylindrical mirror 28 formed with a concentric series of circumferentially extending translucent portions 29 so that the reflected rays of colored light may penetrate 25 these translucent portions 29 and be scattered about the apparatus. This mirror 28 is securely mounted in a rim 30 which has a smooth surface having frictional engagement with a friction disk or wheel 31 mounted upon a shaft 32 spanning the large recess 33 formed in a standard 34, in which recess the disk 31 revolves. The disk 30 is arranged to freely rotate in a bearing consisting of a split ring the adjoined sections 35 30 and 36 of which are formed with rabbeted portions forming a groove in which rim 30 revolves engaged by the ball bearings 37 arranged in said split ring in any suitable manner. The sections 35 and 36 are caused 40 to rest upon the shoulders 38 formed in the standard 34 being secured thereto by any suitable means such as rivets 39. Mounted on shaft 32, exteriorly of the standard is a pinion 40 which meshes with the hereinbefore 45 fore-mentioned bevel wheel 24. It will be understood that member 11 will be mounted similarly to member 12. The cut glass ring 41 shown in Fig. 8 is intended to illustrate one of the variety of ways in which, for the 50 purpose of enhancing the color effects, the members 11, 12, and 13 may be formed, but the essential feature of my invention consists in the novel construction described whereby the prismatic rays may be unfolded, whether pure or mixed, and whereby streams of brilliant light may be emitted from a common source and dissipated in various directions. The utility of this apparatus for the purpose of attracting attention is evident and it is in this aspect that its value as an advertising medium lies.

It will be obvious that various modifications may be resorted to in practice without departing in essential features from the 60 principle of my invention herein disclosed.

I do not intend to limit myself to the exact details of construction except as set forth in the appended claims.

What I desire to claim and secure by Letters Patent is:—

1. A device such as described embodying a plurality of translucent members arranged to be rotated at right angles to each other, a source of light surrounded by said members, and mirrors arranged to reflect the rays 70 of light staggered through said members.

2. A device of the kind described comprising a plurality of translucent mottled members, means for rotating one of said members in a horizontal plane, means for causing said other members to move around said last named member, and a source of light arranged to emit rays upon said members. 80

3. In a device such as described, a plurality of translucent mottled members, 85 means for rotating one of said members in a horizontal plane, means for moving the others of said members around the first named member, a source of light for transmitting rays from said members, 90 and mirrors for reflecting the rays of light transmitted thereto.

4. In combination a standard, a lamp mounted upon said standard, a mottled member revolving around said lamp, mottled members revolving around said first named member at right angles thereto, means for actuating said members, and means for reflecting the rays of light penetrating said members. 95

5. In combination a standard, oppositely arranged mirrors mounted on said standard, a translucent mottled member mounted on said standard between said mirrors, translucent mottled members arranged to revolve 105 around said first-named member between said mirrors, and means disposed between said mirrors whereby rays of light may fall upon said members.

6. A device of the kind described comprising a standard, a post on said standard, a lamp mounted on said post, a translucent mottled ring, a sleeve revoluble around said post, said ring being mounted on said sleeve, and two segmental translucent mottled members arranged to revolve around 110 said ring at right angles thereto. 115

7. In combination a standard, oppositely arranged upright arms mounted on said standard, shafts extending from said upright arms, relatively large bevel wheels mounted on said shafts, translucent mottled segmental members mounted upon said shafts, a translucent mottled ring arranged to rotate between said segmental members, means for 120 rotating said ring and bevel wheels simultaneously, and a source of light emitting rays adjacent said ring and members.

8. A device of the kind described comprising a standard, a lamp post mounted 130

on said standard, a lamp mounted on the top of said standard, a globe around said lamp, a sleeve revolvably mounted on said post, a translucent mottled ring mounted 5 upright on said sleeve, oppositely arranged translucent mottled segmental members, horizontally disposed shafts carrying said members, bearings for said shafts, means for rotating said sleeve and said shafts, and 10 means for reflecting the light penetrating said ring and members.

9. A device of the kind described comprising a standard, an upright post mounted on said standard, a lamp on said post, a vertically disposed translucent mottled ring ar- 15

ranged to revolve around said post and lamp, oppositely arranged horizontally-disposed shafts, a translucent mottled segmental member mounted on each shaft and arranged concentric with said ring, a mirror 20 fixed on each shaft at the rear of said segmental member, and means for rotating said ring and said mirror said members arranged to surround said ring.

In testimony whereof I affix my signature 25 in presence of two witnesses.

CHARLES R. PIERCE.
